UNITED STATES PATENT OFFICE.

ELIZABETH A. DAVIS PRESS, JR., OF WHITE PLAINS, NEW YORK.

DESIGN FOR LACE.

Application filed October 10, 1925. Serial No. 15,085. Term of patent 3½ years.

To all whom it may concern:

Be it known that I, ELIZABETH A. DAVIS PRESS, Jr., a citizen of the United States, residing at White Plains, Westchester County, State of New York, have invented a new, original, and ornamental Design for Lace, of which the following is a specification, reference being had to the accompanying drawing, forming part hereof.

The figure of the drawing is a face view of a piece or section of lace showing my new design.

I claim:

The ornamental design for lace, substantially as shown.

ELIZABETH A. DAVIS PRESS, JR.
